UNITED STATES PATENT OFFICE.

CHARLES CHRISTOPHER HIATT, OF WILMINGTON, OHIO.

AUGER-BIT.

SPECIFICATION forming part of Letters Patent No. 781,652, dated February 7, 1905.

Application filed April 6, 1904. Serial No. 201,935.

To all whom it may concern:

Be it known that I, CHARLES CHRISTOPHER HIATT, a citizen of the United States, residing at Wilmington, in the county of Clinton and 5 State of Ohio, have invented a new and useful Auger-Bit, of which the following is a specification.

This invention relates generally to auger-bits, and particularly to that class known as "central-stem double-cutter" auger-bits.

The object of the invention is to improve the screw of the bit in such a manner as to reduce the power necessary to enter it in the work and to render it possible to keep the 5 point sharp and thus thoroughly effective at all times for accomplishing the purposes designed.

With the above and other objects in view, as will appear as the nature of the invention 0 is better understood, the same consists, generally stated, in an auger-bit having a screw the end of which terminates in a cone-shaped or angle drill-point.

The invention consists, further, in an auger- 5 bit having a screw provided with double threads the ends of which terminate in oppositely-disposed cutting edges presenting a conical point.

The invention consists, further, in a central- 0 stem double-cutter auger-bit having a screw the end of which terminates in a conical double cutting-point.

The invention consists, finally, in the various 5 novel details of construction of an auger-bit to be hereinafter fully described and claimed.

In the accompanying drawings, forming a part of this specification, and in which like characters of reference indicate corresponding parts, there are illustrated two forms of 0 embodiment of the invention, each capable of carrying the same into practical operation, it being understood that the elements therein exhibited may be varied or changed as to shape, proportion, and exact manner of 5 assemblage without departing from the spirit thereof.

In the drawings, Figure 1 is a view in elevation, of a central-stem double-cutter auger-

bit provided with a double-threaded screw having its point made cone-shaped. Fig. 2 is 50 an enlarged detail view of the screw shown in Fig. 1. Fig. 3 is an end view of the screw shown in Fig. 2. Fig. 4 is an enlarged detail view of a single-threaded screw. Fig. 5 is an end view of the screw shown in Fig. 4. 55

Referring to the drawings, 1 designates an ordinary central-stem auger-bit having a single convolute blade 2, a pair of cutters 3, and a screw 4. As the stem and cutters are of the construction common to such bits, further description is deemed unnecessary.

The present invention resides in the improvement in the point of a screw by which its rapid entrance into hard wood may be readily effected with a minimum of labor and 60 which permits of the point being sharpened when it has become blunt. In Figs. 1 and 2 the screw is of the ordinary double-thread type, and the ends of the threads are pitched at opposite angles to each other to form a 65 cone-shaped terminal 5, the edges of the terminal being sharpened to present chisel cutting-surfaces 6. In the form of embodiment of the invention shown in Fig. 5 the screw is of the single-thread type and the terminal of 70 its thread is formed into a half-cone, the inner wall of which is disposed approximately in alinement with the long diameter of the stem. The pitch of the screw-threads are to be determined by the work to be done—that 75 is to say, whether rapid or slow boring is to be effected or whether heavy or light cutting is to be secured. By the provision of the peculiar-shaped point of the screw less resistance is presented to its entering into the 80 wood, and, as before stated, the point may readily be sharpened when it has become 85 blunt.

Having thus fully described my invention, what I claim is— 90

1. An auger-bit provided with a screw-point having a cone-shaped core and two flanges carried around it and constituting cutting-threads, the cutting ends of the flanges being trimmed back from the point of the cone to- 95 ward their outer cutting edges.

2. An auger-bit provided with a screw-point having a cone-shaped core and two flanges carried around it and constituting cutting-threads, the cutting ends of the flanges being 5 trimmed back on a curve from the point of the cone toward their outer cutting edges.

In testimony that I claim the foregoing as

my own I have hereto affixed my signature in the presence of two witnesses.

CHARLES CHRISTOPHER HIATT.
